UNITED STATES PATENT OFFICE.

SILAS HARRIS, OF SAN FRANCISCO, CALIFORNIA, ASSIGNOR TO THE PACIFIC ROLLING MILLS COMPANY, OF SAME PLACE.

RAILWAY-CHAIR.

SPECIFICATION forming part of Letters Patent No. 478,426, dated July 5, 1892.

Application filed October 16, 1891. Serial No. 408,921. (No model.)

To all whom it may concern:

Be it known that I, SILAS HARRIS, a citizen of the United States, residing in the city and county of San Francisco, State of California, 5 have invented certain new and useful Improvements in Railway-Chairs; and I hereby declare the following specification and drawings accompanying the same to be a full, clear, and exact description of my invention.

10 My invention relates to what are known as "railway-chairs," employed for supporting railway-bars and attaching them to the sleepers or ties; and it consists in forming such chairs of two members or parts joined by rivets and having a uniform section bent to such form as to give flat foot-plates at each side, angular diagonal and braced vertical webs in contact with each other near the upper flanges, and a flat bearing area on the 15 top, on which the rails are held by clamp-head bolts at each side.

The object of my invention is to secure a simple and inexpensive manufacture of such chairs and avoid the more expensive processes and implements required with turnover flanges when the whole chair is formed in one piece.

Referring to the drawings, Figure 1 is a perspective elevation of one of my improved 20 railway-chairs with a section of the rail mounted therein and the chair attached to a sleeper or tie in the usual manner. Fig. 2 is an end view of one of my improved chairs, showing its transverse section and with a rail fastened thereon. Fig. 3 is a plan view of 25 the same chair.

Similar letters of reference on the different figures indicate corresponding parts.

The base-flanges A' A² are made to fit on a 30 sleeper or tie and with a bearing area sufficient to prevent crushing the wood beneath and perforated to receive the holding-down spikes B, driven down into the sleeper or tie H in the usual manner.

35 The vertical members or webs C' C² are set at an angle, as shown, so as to give greater lateral stability to the chair, especially on curves, and to enable the two members to be joined by the rivets D at the top, as shown in 40 the drawings.

The top flanges E' E² are formed parallel

to the base-flanges A' A² and of a sufficient width to receive the rail F and also the clamp-bolts G' G², which nip the bottom flanges of the rail F and hold it firmly against strains in 55 all directions.

It will be observed that either of the main members forming the chair is by itself a very simple form that can be produced by common implements in a rapid manner and that 60 when joined by riveting, as shown, the stability and strength of the chair as a whole is not impaired by this method of construction.

Having thus explained the nature and objects of my invention, what I claim as new, 65 and desire to secure by Letters Patent, is—

1. In a railway-chair, the combination of the two duplicate members having parallel top and bottom horizontal flanges and diagonal webs between said flanges, said webs being in 70 contact with each other at a point near the upper flanges and being considerably distant from each other at the point where the bottom flanges rest upon the tie, the rivets D for securing the webs together, as shown, and the 75 clamping-bolts G' and G², which nip the bottom flanges of the rail and hold it firmly against strains, substantially as described.

2. In a railway-chair, the combination of the two duplicate members, one of which has 80 the base-flange A', fitting upon the sleeper, the upper parallel flange E', on which the rail rests, and the intermediate inclined web C', and the other of which has the bottom horizontal flange A², resting on the sleeper, the 85 upper parallel flange E², which supports the rail, and the intermediate inclined web C² between the upper and lower flanges, the rivets D for fastening the two webs securely together at the top, the clamping-bolts G' and 90 G², held in the flanges E' and E² and nipping the bottom flanges of the rail, and the spikes B, which secure the flanges A' and A² to the sleeper or tie, substantially as described.

In testimony whereof I have hereunto af- 95 fixed my signature in the presence of two witnesses.

SILAS HARRIS.
